(57) **CLAIM**

The ornamental design for the molded foam arm chair with slanted arms, as shown and described.

DESCRIPTION

FIG. 1 is a front perspective view of an embodiment of a molded foam arm chair with slanted arms.

FIG. 2 is a front view of the embodiment.

FIG. 3 is a right side view of the embodiment.

FIG. 4 is a left side view of the embodiment.

FIG. 5 is a back view of the embodiment; and,

FIG. 6 is a top view of the embodiment.

Elements of the drawings shown in dashed lines are for illustrative purposes only and form no part of the claimed design.
